UNITED STATES PATENT OFFICE.

ALFRED ROESCH, OF BRIDGEPORT, CONNECTICUT, ASSIGNOR TO DAVIS & ROESCH TEMPERATURE CONTROLLING COMPANY, OF NEW YORK, N. Y., A CORPORATION OF NEW JERSEY.

TEMPERATURE-REGULATOR.

SPECIFICATION forming part of Letters Patent No. 705,613, dated July 29, 1902.

Application filed March 14, 1900. Serial No. 8,590. (No model.)

To all whom it may concern:

Be it known that I, ALFRED ROESCH, a citizen of the United States of America, and a resident of Bridgeport, in the county of Fairfield and State of Connecticut, have invented 5 certain new and useful Improvements in Temperature-Regulators, of which the following is a specification, reference being had to the accompanying drawings, forming a part thereof.

- 10 My invention relates to that class of temperature-regulators in which the actuating means of the heat-controller is controlled, primarily, by a thermostatic device and, secondarily, by pneumatic pressure.
- 15 In carrying out my invention a thermostatic device is first employed to control the movements of a small pneumatic valve of but slight resistance, such valve when opened permitting the escape therethrough of compressed air or other motive fluid to open another pneumatic valve which will permit compressed air to pass therethrough to a steam-valve or similar device controlling a heat-supply. The secondary valve may be arranged 20 to permit the passage therethrough of a larger quantity of motive fluid during a given time than will the primary valve, and a quicker and more positive action of the heat-controller 25 may be thereby attained.
- 30 I have illustrated and described in connection with my invention herein a novel form of thermostatic device, but have made no claim to such thermostatic device in this application, as the same forms the subject-matter of a copending application the serial number of which is 43,188 and the date of filing January 14, 1901.

My invention also consists in improvements in the valves and valve mechanism employed 40 and in certain improvements in construction and combination of parts, as will hereinafter more fully appear.

In the drawings which form a part of this specification, Figure 1 is a front or face view 45 of a temperature-regulator embodying my invention. Fig. 2 is a view in longitudinal section, the plane of section being taken upon the line 2 2 of Fig. 1. Fig. 3 is a view in transverse section, the plane of section being 50 taken upon the line 3 3 of Fig. 1. Fig. 4 is

a detail view showing an enlarged section of one of the air-controlling valves and its contiguous parts. Fig. 5 is a similar detail view, the line of section being taken through the other of the air-controlling valves and its contiguous parts.

Referring in detail to the drawings, reference character 1 designates a suitable base-plate, which is formed of some material, preferably cast-iron, which is but slightly affected by changes of temperature. Supported at one end upon the base-plate 1—as, for instance, upon an uprising lug 20—is a thermostatic member 2, here shown as a single thin metallic plate. This plate may be of brass or of 60 other metal or metallic compound, which is of greater expansibility under the influence of a rise in temperature than the supporting-base. The opposite end of said metallic strip 2 is secured to a stud 21, depending from a lever, hereinafter referred to as the "primary" lever and which lever as a whole is designated by the reference character 16. The primary lever 16 is pivotally supported upon uprights 17, made integral with or rigidly secured upon the supporting-base. The pivots, which may conveniently be adjustable cone-points, are designated by the reference character 18. The primary lever has a long arm 22, one end of which is adapted to control the 65 movements of a valve or valves, to be herein-after more fully described, and a short arm or extension 15, between which and the base is arranged a compression or return spring 19.

From the foregoing it will be seen that under the influence of a decrease in temperature the metallic strip 2 will contract and being rigidly secured to the base at 20 will pull upon the stud 21 and rotate the lever 16 upon its pivots 18. This will raise the end of the arm 70 22 of the lever 16 and depress the arm or extension 15 against the pressure of the spring 19. A rise of temperature and a consequent expansion of the strip 2 will permit the spring to react and force the lever back and lower 75 the arm 22. A regulating-screw 23 is supported in a screw-threaded bracket 24, which is rigid with the base 1. The end of the screw is arranged to bear against the strip 2, as 80 shown in Fig. 2, and when it is desired that 85

the thermostat shall act more quickly or at a lower temperature the said screw is adjusted to bear harder against the said thermostatic strip, with the result that the same is forced 5 out of a straight line, and hence relatively shortened. A pointer or indicator 25 may be secured to the said adjusting-screw and a dial 26 provided, having the degrees of temperature marked thereon corresponding in 10 position to the position the pointer will assume when the regulating-screw has adjusted the thermostat to operate at such degrees.

An air-chamber 3 is provided in the base 1, which air-chamber is in open communication with a reservoir 4, forming a source of compressed-air supply. The said communication is through an air-duct 5. A valve 6' controls egress from the said air-chamber 3 to a secondary air-chamber 28, as hereinafter 20 set forth. The primary lever carries an exhaust-valve 7, the said exhaust-valve 7 and inlet-valve 6' being arranged through connecting-pin 8 to act synchronously in both directions. The valve 7 is here shown as mounted 25 in a shouldered orifice in the arm 22 of the lever 16 and retained therein by a strip 40.

The secondary air-chamber 28, before referred to, is provided in the base 1, and a diaphragm 29 is in combination with such chamber. A lever 31, hereinafter referred to as the "secondary" lever, is provided and is pivoted at 39 to lugs 38 upon the base 1. One 30 end of said lever bears against the follower 30 in engagement with the diaphragm 29, and the other end controls valves 33 and 34, corresponding with valves 6' and 7. A spring 37 normally tends to lift the lever 31 and to raise the valve 34 from its seat. A pin 32 is arranged between the valves 33 and 34, and a 40 spring 36 tends normally to close the valve 33, and hence acts in opposition to the spring 37.

In Fig. 2 I have shown one end of a steam-radiator as a portion of a heating system and a heat-controller in the form of a steam-valve 45 14. Actuating means for the steam-valve is shown in a diaphragm-chamber 6, a diaphragm 11, a follower 12, secured to the stem of the steam-valve 14, and a return-spring 13. Compressed air introduced into the dia- 50 phragm-chamber 6 will depress the diaphragm 11 and close the valve 14. An exhaustion of the air in said chamber will permit the spring 13 to act, and the valve 14 will be opened. An air-duct 10 is arranged between the air-chamber 55 3 in the base 1 and the diaphragm-chamber 6.

The device will operate then as follows: A rise in temperature of the medium surrounding the thermostatic strip 2 will cause same 60 to expand relatively to the base, and the spring 19 will rock the lever 16 until the exhaust-valve 7 is closed and the inlet-valve 6' is opened. This will permit air under pressure to pass along the duct 27 to the secondary 65 chamber 28. Air under pressure in the chamber 28 will raise the diaphragm 29, which will rock the lever 31, closing the exhaust-valve

34 and opening the inlet-valve 33. Air under pressure will then be admitted through the duct 10 from the chamber 3 to the chamber 6 70 of the heat-controller, and the steam-valve 14 will thereby be closed. A reduction of temperature surrounding the thermostatic strip 2 will have the contrary effect of causing the exhaust-valve 7 to open and the inlet-valve 6 75 to close, whereby air will be exhausted from the secondary chamber 28, and hence will cause the exhaust-valve 34 to open and the inlet-valve 33 to close, whereby air will be exhausted from the chamber 6 of the heat- 80 controller. The duct controlled by the valves 33 and 34 may be larger than that controlled by the valves 6' and 7, and in such case a larger quantity of motive fluid will be allowed to pass along the duct 10 in a given 85 time than would be permitted were the fluid delivered directly from the duct 27. By this means the heat-controller may be operated quickly, which, if the same be a steam-valve, is very advantageous. 90

By means of the construction herein set forth I am enabled to employ a thermostatic device which is exceedingly sensitive and yet quickly and positively operate a heat-controller requiring considerable power in its 95 operation.

I do not desire of course to be limited only to the precise construction and combination of parts as herein set forth, as the same is obviously but one embodiment of my invention. 100

What I claim is—

1. In a temperature-regulator, the combination with the base having a primary and a secondary chamber therein, a duct leading 105 from said primary chamber to said secondary chamber and therefrom to exhaust, and another duct leading from said primary chamber and adapted to connect with the actuating means of a heat-controller, and therefrom 110 to exhaust, the said primary chamber in open communication with a source of fluid-pressure supply, of a primary and a secondary lever supported upon said base, a thermostatic device for controlling the movements 115 of the primary lever, a diaphragm in communication with said secondary chamber, for controlling the movements of said secondary lever, two spring-actuated inlet-valves within 120 said primary chamber, one for each duct leading therefrom, an exhaust-valve carried by each of the said levers, and stems between the said inlet and exhaust valves, whereby the valves for said first-mentioned duct are controlled by the movements of the primary 125 lever, and the valves for the second-mentioned duct are controlled by the movements of the secondary lever, substantially as set forth.

2. In a temperature-regulator, the combination with a base having a primary and a secondary chamber therein, two ducts leading from within the said chamber to exhaust, one of the said ducts being of larger size

than the other, a branch duct leading from the smaller of said ducts to the secondary air-chamber, and a branch duct leading from the larger of said ducts and adapted to connect with the actuating means of a heat-controller, the said primary chamber in open communication with a source of fluid-pressure supply, of a primary lever supported upon said base, a thermostatic device for controlling the movements of the said lever, a secondary lever supported upon said base, a diaphragm, in communication with said secondary chamber, for controlling the move-

ments of said secondary lever, and inlet and exhaust valves arranged at opposite ends of both of the two first-mentioned ducts, the valves for the smaller duct controlled by the primary lever, and the valves for the larger duct controlled by the secondary lever.

Signed by me at New York, N. Y., this 21st 20 day of February, 1900.

ALFRED ROESCH.
